UNITED STATES PATENT OFFICE.

BENJAMIN F. STEWART, OF CHICAGO, ILLINOIS.

GAS-ENGINE.

No. 857,120.

Specification of Letters Patent.

Patented June 18, 1907.

Application filed September 2, 1904. Serial No. 223,119.

To all whom it may concern:

Be it known that I, BENJAMIN F. STEWART, a citizen of the United States, and a resident of Chicago, county of Cook, and State of Illinois, have invented certain new and useful Improvements in Gas-Engines, of which the following is a specification, and which are illustrated in the accompanying drawings, forming a part thereof.

This invention relates to the two-cycle type of gas engine; and its object is to provide for the compression of the air for each charge before introducing the combustible material, the latter being delivered to the passage through which the air enters the exploding chamber.

A further object is to provide for the regulation of the air supply in a two-cylinder engine.

The invention consists in the structure hereinafter described and which is illustrated in the accompanying drawings, in which—

Figure 1 is a longitudinal section of the engine on the plane of the crank shaft; Fig. 2 is a plan section on the line 2—2 of Fig. 1; Fig. 3 is a plan section on the line 3—3 of Fig. 1; Fig. 4 is a longitudinal central section on a plane transverse to that of Fig. 1; and Figs. 5 and 6 are details of the valve controlling the fuel supply.

While the major part of the invention is applicable to a single cylinder engine, I have shown, in the drawings, a two-cylinder engine, or, more properly, a pair of engines comprised within a single casting. As the two cylinders are essential duplicates the description is, for the most part, restricted to one of them.

There are shown in the drawings two cylinders, 10 and 11, cast together and provided with a jacket 12 which envelops the ends of the cylinders within which the combustion takes place, and provides for cooling the same. The crank shaft is shown at 13 and is common to the two cylinders, as are also the exhaust chamber 14 and the air-supply chamber 15, which are shown as located between the two cylinders. The piston is shown at 16, its pitman at 17, and crank at 18.

The crank is located within the compression chamber, the casing of which is shown at 19 and to which air is admitted through the port 20, leading through the cylinder wall from the chamber 15, and is uncovered by the piston when the latter is at the limit of its stroke. The air is compressed by the piston

during its outstroke, and is delivered from the compression chamber to the explosion chamber through a passage 21, cored in the walls of the engine and opening into the combustion chamber through the port 22, which is uncovered by the piston as it reaches the limit of its outstroke. The exhaust port 23 is also uncovered at the same time and leads to the exhaust chamber 14. A baffle plate 24 rises from the face of the piston 16 in front of the port 22, so as to deflect the incoming charge into the body of the explosion chamber and prevent it from passing out of the exhaust port with the burned charge.

The fuel, usually gasoline, is admitted to the passage 21 at 25, entering through a duct 26 in a plug 27, having a nipple 28 adapted to be connected with the fuel tank. The duct 26 opens through the inner end of the plug 27 and is controlled by a valve 29, the stem, 30, of which passes outwardly through the plug and carries at its outer end an expansion spring 31, which holds the valve to its seat. The valve is unseated by the suction due to the instroke of the piston, and to facilitate this action the plug 27 is preferably recessed so that air may be admitted through the duct 32 to the back of the valve 29. As the liquid enters through the duct 26 it will trickle down the walls of the passage 21 and will then be taken up by the air as it rushes through this passage to the explosion chamber.

While a small quantity of air will be admitted by the rising of the valve 29, it will not be sufficient to combine with the liquid to form an explosive mixture, and I am therefore able to accomplish the compression of the air before it becomes charged with the fuel and hence avoid danger of explosions within the compression chamber, as the charge does not become explosive until it enters the chamber of the cylinder.

The air supply, in an engine organized as described, may be regulated by means of a U-shaped slide valve 33, located within the chamber 15, and being made of elastic material so that it automatically closes the air induction ports 20 for each cylinder. This valve may be provided with a stem 34, by means of which it may be adjusted, and its own elasticity will hold it in any position in which it may be set.

In casting the shell of the pair of engines integral a journal box 35 is provided for the crank shaft 13 intermediate of the two

cranks, and in order that this box may be the better reinforced and supported I space the two casings 19, 19, of the compression chamber, apart, thereby providing a supporting plate at each end of the box.

I claim as my invention—

1. In a gas engine, in combination, a pair of power cylinders cast integral, a compression chamber for each cylinder, an air chamber between the cylinders, a port leading from the air chamber to each compression chamber.
2. In a gas engine, in combination, a pair of power cylinders cast integral, a compression chamber for each cylinder, an air chamber and an exhaust chamber between the cylinders, ports opening from the air chamber to each compression chamber, and ports connecting the exhaust chamber with the explosion chamber of each cylinder.
3. In a gas engine, in combination, a pair of power cylinders cast integral, a reciprocating piston in each cylinder, a compression chamber at the outer end of each cylinder, an air chamber between the cylinders and adjacent the outer end thereof, an exhaust chamber between the cylinders and adjacent the inner ends thereof, ports leading from the air and exhaust chambers through the walls of each cylinder and so arranged as to be un-

covered alternately by the pistons at the ends of their strokes.

4. In a gas engine, in combination, a pair of power cylinders cast integral, a compression chamber for each cylinder, an air chamber between the cylinders, a port leading from the air chamber to each compression cylinder, an expansible U-shaped double slide valve fitted within the air chamber and adapted to cover its ports.

5. In a gas engine, in combination, a pair of juxtaposed power cylinders, a compression chamber for each cylinder, an air chamber between the cylinders, and a port leading from the air chamber to each of the compression chambers, the ports being controlled by the pistons of the cylinders and being opened alternately.

6. In a gas engine, in combination, a pair of cylinders having a common wall, a compression chamber for each of the cylinders, an induction passage formed in the wall between the cylinders, and a port leading from the passage to each of the compression chambers.

BENJAMIN F. STEWART.
